UNITED STATES PATENT OFFICE

2,399,818

ADJUSTABLE PLOW

John R. Michael, Arab, Ala.

Application January 26, 1944, Serial No. 519,785

1 Claim. (Cl. 97—198.1)

This invention relates to an adjustable plow, cultivator, or the like, and is applicable to all types of plows, particularly the walking, riding and tractor types.

It is especially aimed to provide a structure which will permit adjustment after the back band of the harness has been adjusted to the proper angle so that if the plow is not exactly adjusted as it should be for proper draft and smooth running, it can then without stopping the plow, if so desired, be accurately adjusted, especially to save the draft animal much discomfort, injuries and sores.

More specifically, I aim to provide a structure wherein the plow standard is pivotally mounted on the beam and coacts with means connected to the beam and to the standard manually operable to effect the desired accurate adjustment.

It is further aimed to provide a novel form of clevis for the plow beam, particularly enabling reversal whereby it may be disposed for the more direct and efficient draft and also be adapted for continuous use in the event one side becomes broken or injured.

The more specific objects and advantages will become apparent from a consideration of the description following taken in connection with accompanying drawings illustrating an operative embodiment.

In said drawings:

Figure 1 is a view in side elevation of a plow beam, the standard and plow being constructed in accordance with the invention;

Figure 2 is an enlarged view taken approximately longitudinally, vertically and centrally;

Figure 3 is an enlarged sectional view taken on the line 3—3 of Figure 2;

Figure 4 is a horizontal sectional view taken on the line 4—4 of Figure 2;

Figure 5 is a detail side elevation of the clevis and adjacent parts of the plow beam; and

Figure 6 is an enlarged vertical sectional view taken on the line 6—6 of Figure 1.

Referring specifically to the drawings wherein like reference characters designate like or similar parts, 10 designates a conventional plow beam on which a plow standard 11 is pivotally mounted by a removable bolt as at 12. The structure shown is of the walking type, although it may be just as well of the riding, tractor, or other types.

A clevis is provided at 13 which is preferably made in a single piece and has an attaching plate at 14 provided with screw-threaded openings at 15 which are engaged by the adjacent threads of a bolt 16, preferably having a manually oper-

able head 17. Extending from the clevis centrally of the plate 14 is an arm 18 which occupies a slot 19 in the beam 10, to generally brace the connection. Particular attention is called to the fact that the clevis has two openings 20 disposed equidistantly on opposite sides of the longitudinal center line of the clevis. As a result of this construction, the clevis may be placed in the most advantageous position relative to the band of the harness and in the event of breakage of the clevis at either opening, the clevis may be reversed while the bolt 16 is removed, and in connection with the manipulation of the bolt 16, this object may be accomplished by hand without the necessity of using tools.

The plow standard 11 has spaced arms 21 disposed one on each side of the beam 10, and providing a vertical slot as at 22 which receives a bolt 23, removably clamping a shovel 24 in place, the illustration of which is to be taken as representative since the shovel may be for plowing or cultivating, of diamond-point form, round-point form or otherwise, and whether adapted for truck farming, general farming, or the like.

An inverted U-shaped saddle at 22 has elements 23 screwed into the lower end thereof at 24, and which elements extend into openings 25 of the arms 21 and thus pivotally mount or suspend the standards 11.

A wear plate 26 is disposed on the top of the beam 10 and it is secured in place by screws or other fastenings 27 which also pass through anchoring plate 28 for a bolt 29. Such plate has a central raised portion 30 beneath which the head 31 of the bolt is disposed, and through which an opening 32 is provided with the shank of the bolt 29 extending loosely therethrough. The screw threads of the shank of the bolt 29 engage the screw threads at 33 in an opening at the top of the saddle 22, so that turning of the bolt in the opposite directions will raise or lower the saddle 22, pivotally moving the standard 21 on its axis at bolt 12 and regulating the depth of the shovel 24.

Threaded on the bolt 29 is a nut 34 which must be loosened when the bolt is turned and which is adapted for movement against the saddle 22 to prevent accidental turning of the bolt. Nut 34 is preferably provided with wings at 35 whereby it may be manually manipulated. To enable efficient turning of the bolt 29, a hand wheel 36 is preferably secured thereto, detachably and in any suitable manner.

It will be clear that the bolt 29 and associated parts may be of any desired size or strength de-

pendent on the parts employed and the work to be performed.

Various changes may be resorted to provided they fall within the spirit and scope of the invention.

I claim as my invention:

In combination with a beam and shovel-mounting standard pivoted thereon, a saddle pivoted to the standard, means operable to move the

5 saddle relatively to the beam to adjust the position of the shovel, comprising a bolt threaded to the saddle, means mounting the bolt on the beam for rotation and against sliding movement comprising an anchor plate, an operating element on the bolt to afford leverage to turn the same, and a lock nut threaded to the bolt and engageable against the saddle.

JOHN R. MICHAEL.
